CLAIM

The ornamental design for a prismatic light transparent toothpick, as shown and described.

DESCRIPTION

FIG. 1 is a perspective view of a prismatic light transparent toothpick showing my design;

FIG. 2 is a front elevational view thereof;

FIG. 3 is a rear elevational view thereof;

FIG. 4 is a top plan view thereof, on an enlarged scale;

FIG. 5 is a bottom plan view thereof, on an enlarged scale;

and,

FIG. 6 is a side elevation thereof.

The characteristic feature of the design resides in a contrasting appearance of the top and bottom of the toothpick resulting from the prismatic affect caused by light passing through the toothpick.
